UNITED STATES PATENT OFFICE.

GEORGE W. MCGILL, OF NEW YORK, N. Y.

METALLIC FASTENER.

SPECIFICATION forming part of Letters Patent No. 330,995, dated November 24, 1885.

Application filed September 25, 1885. Serial No. 178,126. (No model.)

To all whom it may concern:

Be it known that I, GEORGE W. MCGILL, of New York, (Riverdale,) in the county of New York, and State of New York, have made certain new and useful Improvements in Metallic Fasteners, of which the following is a full and exact description, reference being had to the accompanying drawings, making part of this specification.

10 The object of my invention is the production of an improved metallic fastener for fastening or binding together papers, cloth, and such like material; and it consists of a fastener formed of a piece of round or flat wire of suitable length, folded in its center, preferably having its end pointed, and having its folded center secured in a metal disk, the disk forming the head of the fastener, and the folded wire its penetrating or fastening shanks.

15 20 In the drawings, Figure 1 represents the folded wire or fastener-shanks, vertically and in cross-section on the line *xx*. Fig. 2 represents the metal disk or fastener-head.

The wire, as shown in Fig. 1, is round wire, 25 pointed at the ends and folded in its center at *a*, so as to bring both halves *b b* of the wire into close parallel contact, with one end or point projecting a little beyond the other, for a purpose hereinafter explained.

30 The disk, as shown in Fig. 2, consists of a piece of suitable ductile metal, *C*, having a depression, *c'*, struck or sunk in the center of one of its sides. The wire so folded is placed in a die, *K*, having a chamber, *d*, running vertically through its center, and of a size and shape to receive the folded wire, as shown in Fig. 3, and its face fashioned as shown in Fig. 6, Fig. 6 being a top or plan view of the face of the die, and Fig. 3 a vertical section showing the folded wire in the vertical chamber *d* of the same. The face of the die has a concave center, *e*, surrounding the top of the chamber *d*, and a convex cheek, *g*, surrounding the concave center *e*. The fold *a* of the wire occupies the center of the concave center *e*.

45 A metal disk, formed as described, is placed on the cheek *g* of the die, with the top of the fold *a* of the wire occupying its depressed or sunken center, *C'*, as shown in Fig. 4. A 50 swaging-die, *J*, is now brought with force upon the top of the metal disk, giving to its

upper surface the form of the face of the swaging-die, and to its lower surface the form of the face of the lower die, and in doing so drawing or reducing the thickness of the disk, 55 increasing its diameter and forcing its central thickness or bulk down in the concave center *C'* of the lower die, and forming a clamping-collar, *h*, in, around, and below the fold *a* of the wire shank, which is thereby securely 60 locked in the disk, as shown in Fig. 5, the disk forming a solid head for the same, as shown in the sectional Fig. 7 and reversed Fig. 8, and completing the fastener.

The metal disk or top of the fastener may 65 be given a variety of ornamentation by fashioning the face of the swaging-dies accordingly.

Fig. 9 represents an edge and side view of the fastener-shanks, made of flat wire or sheet 70 metal and folded, as shown in Fig. 1.

The shanks of the fastener may be formed of two separate strips of metal, which, on being put together in the heading-die, may be headed in the manner hereinbefore described; 75 but I give preference to having the shanks formed of a single strip of wire or flat metal folded near the center, as before described.

In practice I find that in swaging the metal disk upon the fold *a* of the shanks the fold is 80 eyed a little, forming a slightly-projecting head, which, when surrounded by the center collar, *h*, of the disk, produces a very secure attachment, and when two separate strips are used the force used in drawing or driving 85 down the disk slightly spreads the tops of the shanks, heading them sufficiently to secure a very strong connection between them and the disk or fastener-head.

The fastener thus constructed is put in operation by forcing its shanks through the papers or other articles desired to be bound, and separating the shanks and folding them down on the other side of the same, thereby binding the article between the folded-down shanks 95 and the head of the fastener.

One of the shanks of the fastener is made longer than the other, to facilitate the ready separation of the same in the act of using.

I do not claim herein the process or dies 100 herein described as used in producing my invention, as I propose applying for a separate

patent therefor, and for certain automatic machinery in which said dies are used and such processes carried out; but

What I do claim herein, and desire to secure by Letters Patent, is—

A metallic fastener consisting of a penetrating part composed of two projecting shanks of metal, and a metal button-shaped head secured to the shanks by an integral collar

swaged in the under center surface of the head 10 and surrounding and clamping the top of the shanks, substantially as and for the purposes described.

GEORGE W. MCGILL.
